UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,062, dated September 9, 1902.

Application filed July 29, 1902. Serial No. 117,581. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front view.

The leading features of the design consist of a frame, the sides and cross-piece of which have plain inner and outer borders. The cross-piece is in the shape of a hood centrally disposed, upon which is a casket-like figure having flutings edged with scrolls extending from the lower corners. Extending centrally from these flutings are branched volutes or scrolls with foliation springing therefrom. Extending across the scrolls and down the sides of the frame and caught up at center by streamers and intermediately by the scrolls are garlands of flowers. Hung from the ends of the garlands on the sides are swinging censers, and below the censers, at the lower ends of the sides, are crossed scrolls. The center or summer front has a raised beaded line near its outer edges, formed of straight portions ending at the corners in

volutes, between which and extending inwardly at each of the four corners is a trefoil. Disposed centrally within the border is an oval molding containing the representation of an altar, upon which is standing the figure of a child. Kneeling at the side of the altar, holding a little child, is the figure of a woman. Extending from the sides of the oval centerpiece are ornamentations pierced by torches bearing streamers. Below the summer front is the grate-front, the sides of which are formed of scrollis resembling somewhat an urn in configuration. Between the sides of the frame, the frame is formed of open-work, the panel intermediate the openings being ornamented. Over the openings are small hooded portions. Below the grate-front and extending forwardly is another open-work frame having rounded corners and end ornamentations and a lower convex border-piece.

I claim—

The ornamental design for a fireplace-front as herein described and shown.

In testimony whereof I have hereunto set my hand in the presence of two subscribing witnesses.

THOMAS M. DUDGEON.
